MASSACHUSETTS.

COMBINED HEATING AND SPRINKLING SYSTEM.

1,289,236.

Specification of Letters Patent. Patented Dec. 31, 1918.

Application filed March 16, 1914. Serial No. 824,840.

To all whom it may concern:

Be it known that we, CHARLES P. NUTTER, a citizen of the United States, and resident of Malden, county of Middlesex, State of Massachusetts, and JOHN E. CHATMAN, a citizen of the United States, and resident of Swampscott, county of Essex, State of Massachusetts, have invented an improvement in combined heating and sprinkler systems in which there are provided air-chambers for insulating the sprinkler-heads from the heat of the circulating water and in the process or method of filling or installing such systems, of which the following description, in connection with the accompanying drawings, is a specification, like characters on the drawings representing like parts.

Our invention is adapted for use in connection with a combined heating and sprinkler system such as is shown, for example, in our Patent No. 1,087,136, issued February 17, 1914, and is designed to render more effective the heat insulation means shown in said patent. Said patent shows as a preferable means for insulating a sprinkler head from the heat of the water circulating through the system an air chamber formed in a nipple connecting the sprinkler head with the sprinkler pipe. Our present invention is designed to increase the length of the operative air column so provided without increasing the length of the nipple, and thus to render the heat insulation provided by the air chamber more complete and perfect.

Figure 1 is a vertical section through a building provided with a combined sprinkler and heating system showing the system diagrammatically. Fig. 2 is a detail of a sprinkler head connected to the sprinkler pipe and provided with one form of air chamber for insulating the sprinkler head from the heat of the water in the pipe. The air chamber and the connection between the sprinkler head and the sprinkler pipe may be, however, any one of many different forms, without affecting the applicability of this invention.

Referring to Fig. 1, *a* indicates the connection to the water supply main, *b* indicates the heater for heating the water in circulation, *c* indicates the supply riser, *d*, *d* represent the floors of the building, *e*, *e* represent sprinkler pipes on which are mounted sprinkler heads *f*, *f*, *g* is the return riser completing the circulation loop, *h* is a

supply pipe connecting the system with an expansion or pressure tank *r*, in which the normal water level under operating conditions is represented by the line *y*—*y*, *i*, *i* represent air-cocks located at the highest points 60 of the system, for venting the system of air, and *j*, *j* are air-cocks in the individual sprinkler pipes, preferably located between the sprinkler heads on the pipes and the inlet ends of the pipes, *i. e.*, the ends from which 65 the circulating water enters those pipes. These sprinkler pipes are preferably slightly inclined upwardly from the inlet ends in the manner usual to hot water heating systems. In the illustration the inclination is greatly 70 exaggerated, for the sake of clearness. *k* is a check valve interposed in the connection between the system and the supply main in the manner usual to sprinkler systems. *l* is a by-pass around the check valve, in which 75 is placed the supply pump *m*. *n*, *n*, *o*, *o*, *p*, *p* and *q*, *q* are gate valves at various points in the system.

Referring to Fig. 2, *s* is a nipple connecting the sprinkler pipe *e* with the sprinkler head *f* and adapted to contain the insulating air chamber *t*.

If when the water from the supply main *a* is turned on so as to fill up the system, the vents *i*, *i* be open so as to allow the air in the system to pass out freely, it is apparent that the pressure on the supply main will cause the water to fill the risers and sprinkler pipes throughout the building, leaving in the system only such air as has been trapped in the 90 nipples *s*, and that the air trapped in the nipples will have been trapped at substantially atmospheric pressure in each instance. An increase in the pressure on the trapped air in the nipple will therefore compress it, 95 and decrease the length of the air column within the nipple and the effectiveness of the heat insulation. Such an increase of pressure on the trapped air will occur as the water rises in the system under the pressure of the water supply, and finally, when the system is filled and the vents closed, the pressure on the air will be the full pressure of the water supply, which greatly exceeds the atmospheric pressure. As a result, the insulating air columns in the various nipples throughout the building will be compressed and shortened, the degree of such compression and shortening depending in each case 100 upon the position of the particular air cham- 110

ber in the building, the pressure being greater in the basement and lower floors than in the upper floors. All of the nipples will be filled partially with air and partially with water. It is obvious that any difficulty arising from this situation can be avoided by making the nipples long enough in each case so that the length of the air column as it finally stands when the pressure is on in 10 the system will be sufficient for heat insulating purposes.

Our present invention, however, is designed to obviate the difficulty in a different and superior manner.

15 If when the water from the supply main is turned into the system the vents *i*, *i* and *j*, *j* be closed, so that no air can escape from the system, the result will be that the water will rise in the pipes, forcing the air upward and compressing it, until the pressure of the air in the system is sufficient to counterbalance the pressure of the water supply. When the air pressure equals the water pressure, a condition of equilibrium will be 20 established, with the water standing, for example, at the levels indicated by the line X—X, Fig. 1. If now a vent *i* be opened sufficiently to allow the air to escape very gradually, the water will slowly rise 25 throughout the system, and, as it rises, will trap the air in the various nipples *s*, *s*, just as before, but with the difference that by this method the air will have been trapped in any given nipple under substantially the full pressure caused by the pressure in the 30 water supply under normal operating conditions at the particular point where that nipple is located. The air column in the nipple will therefore not be compressed any further 35 when the system is entirely filled with water and is in operation, but will continue to occupy the full length of the nipple.

Accordingly, in operating under our invention we first open the connection between 40 the water supply and the system and allow the water to enter the system under normal pressure, in the meantime keeping the vent closed and retaining all of the air in the system. When the condition of equilibrium 45 has been established, and the inflow of water into the system has ceased, we open the vent slightly and allow the air in the system to escape and the water to rise very slowly and gradually, closing the vent again when the 50 water has risen and driven out all of the air in the system except that trapped in the air chambers. The same result can be accomplished by venting the air in the system through the vents *j*, *j*, instead of 55 through the vents *i*, *i*. If the vents *j*, *j* are to be used, the vent in the lowermost sprinkler pipe will be opened first and closed when the water rises to its level, and then the vent in the next higher pipe will be 60 opened, and so on.

By reason of the large cubical contents of the heater *b* in the basement with relation to the cubical contents of the piping throughout the building, the condition of equilibrium will ordinarily be established 70 before the water has risen to a level as high as that of the lowest sprinkler pipes in the system. If, however, in any case the relative capacity of the boiler and of the piping in the system be such that if the system be 75 filled in the manner described above, the water will have risen above the level of the lowest sprinkler pipes before the condition of equilibrium is established, so that the air in the nipples connected to such sprinkler 80 pipes will be trapped while at a pressure less than the full normal pressure of the system, additional air can be forced into the system by closing the valves *n*, *n* when the heater has been filled with water, draining off the 85 water from the heater and allowing the heater to become filled with air, and then opening the valves *n*, *n* again. By this means, enough air can be forced into the system to make the water level, when equilibrium is established, as low as may be desired.

If the pressure in the main supply is not sufficient to fill the tank *r* to the level desired to be maintained therein under operating 95 conditions, so that a supply pump *m* is required in order to fill it, the pump may be put into operation in the filling of the system and its action so regulated as to fill the pressure tank to the normal level before the 100 air-vent is opened, and to maintain it at this level while the air is escaping through the vent.

Our invention includes, as well as the process above described, the system itself, 105 embodying the insulating air chambers completely filled with air under the pressures normal to the system.

We have spoken of air as the insulating agent, but it is apparent that the principle 110 could be applied with other gases, as for instance, nitrogen, if desired, and such substitution could be made without in any manner departing from our invention.

What we claim as new, and desire to secure by Letters Patent, is:

1. The method of filling air chambers provided in a combined sprinkler and heating system for insulating the sprinkler heads from the heat of the circulating water, 115 which consists in filling said chambers with air under substantially the pressures normal to said chambers under operating conditions and trapping it in said chambers while under such pressure by admitting water to the 120 system.

2. The method of filling a circulating 125 sprinkler system provided with air chambers for insulating the sprinkler heads from the heat of the circulating water, which con- 130

sists in admitting the water to the system and so regulating the escape of air from the system when the water is admitted into the system that the air in said chambers is 5 trapped under substantially the pressures normal to said chambers under operating conditions.

3. The method of filling a combined 10 sprinkler and heating system provided with air chambers adapted to insulate the sprinkler heads from the heat of the circulating water, which consists in forcing water into the system under the pressure normal under operating conditions, and so regulating the 15 escape of air from the system that the air in said chambers is trapped under substantially the pressures normal to said chambers under operating conditions.

4. The method of filling a circulating 20 sprinkler system provided with air chambers for insulating the sprinkler heads from the heat of the circulating water, which consists in opening the connection between the system and the water supply and so regulating the escape of air from the system 25 that the pressure within the system during the escape of the air is at all times substantially the full pressure normally caused in

the system by the pressure in the supply main, whereby the air in said chambers is 30 trapped under substantially the pressures caused at said chambers by the pressure of the water in the supply main.

5. The method of filling a circulating 35 sprinkler system provided with air chambers adapted to insulate the sprinkler heads from the heat of the circulating water, which consists in opening the connection between the system and the water supply, retaining all the air in the system until a state of substantial equilibrium has been established, and then allowing the air gradually to escape from the system, whereby air is 40 trapped in said chambers under substantially the pressures caused at said chambers 45 by the pressure of the water in the supply main.

In testimony whereof, we have signed our names to this specification in the presence of two subscribing witnesses this 14th day 50 of March, 1914.

CHARLES P. NUTTER.
JOHN E. CHATMAN.
